GAME OFFICIATING DEVICE

Thomas H. Filmore, Springfield, Mass.

Application June 25, 1940, Serial No. 342,233

9 Claims. (Cl. 177—384)

My invention relates to mechanism for the control of play in such games as hockey, basket ball, and the like.

It has for one object the provision of means by which the official charged with the duty of supervising and controlling the play may do so from a vantage point removed from the field of play itself.

With this general object in view a further object is to improve the quality of the officiating by giving to the official a more comprehensive view of the play.

Other and further objects and advantages will be apparent from the following specification and claims.

My invention has particular application to games where the play is especially fast such as hockey and basket ball. In hockey for example, the movement of the players is exceedingly swift, and the changes of position of the players, the development and alteration of player formations, and the movement of the puck, take place with great rapidity. It has proved a practical impossibility for an official positioned on the ice to completely and adequately follow the play. Many infractions of the playing rules clearly observed by the spectators go uncalled by the official simply because the latter cannot see them. As a result merited penalties are not imposed and unjustified charges of incompetence and favoritism are leveled at the official. As will be later apparent, these and other difficulties are overcome by the use of my invention.

In the accompanying drawing in which my invention is illustratively applied to the game of hockey,

Fig. 1 is a diagrammatic plan view of a hockey rink embodying my invention;

Fig. 2 is a fragmentary sectional view substantially on line 2—2 of Fig. 1;

Fig. 3 is an illustrative wiring diagram showing one manner of operating the controls using three sets of indicator lights; and

Fig. 4 is an illustrative diagram indicating an alternative form in which two sets of lights are used.

Referring to the drawing, the ice playing field is indicated at 10 and is surrounded by a fence 11 which may be of usual or desired construction, the goal nets are indicated at 12, and the "blue lines" at 13 and 14. It will be understood that approved practice will be followed in regard to the dimensions of the field.

In carrying out my invention I provide at intervals around the fence 11 a plurality of signal

lights generally indicated at 15. As indicated in Fig. 2 these lights are carried in recesses or boxes 16 opening toward the playing field, the openings being provided with protective glass, wire screening or other transparent or translucent covers 16' which are set flush with the boards of fence 11. As shown in Figs. 1, 2 and 3, each box 16 is provided with three colored electric bulbs designated Y, R, and G, which for purposes of description may be considered to represent the colors Yellow, Red and Green, although it will be understood that other color combinations may be used.

As will shortly be more fully described, the yellow lights are wired in parallel in a single circuit controlled by a single switch 18 conveniently placed in control box 19 so that when switch 18 is closed all of the yellow lights are lighted. The red lights are similarly controlled from switch 20 in the control box. The green lights are wired in parallel in groups, the green lights in the boxes 16 at the four end positions or stations *a* being controlled from switch A, the opposed pair at stations *b* by switch B, and groups *c*, *d*, *e*, and *f* by switches C, D, E, and F, respectively, all positioned in control box 19.

Referring to the diagram of Fig. 3, a common return for all of the lights is indicated at 25. A lead for the yellow lights is shown at 26 and is connected to a main lead 27 through switch 18. The lead for the red lights is shown at 28 and is connected to the main lead 27 through switch 20. The green lights of group *a* are connected to lead 29 which is connected to the main lead 27 through switch A. The green lights of group *b* are connected to a lead 30 which is connected to main lead 27 through switch B. The green lights of group *c* are connected to lead 31 which is connected to main lead 27 through switch C. Similarly leads 32, 33, and 34 respectively connect groups *d*, *e*, and *f* (not shown in the diagram) to the common lead 27 through their respective switches D, E, and F.

As above stated, all of the control switches are grouped in the control box 19. The control box is placed in a position sufficiently remote from, and sufficiently elevated above the playing field so that the official operating the controls has a full and adequate view of the field and the players thereon.

In operation when the official notes an offside play he closes switch 18, thus lighting the yellow lights in all the boxes 16, indicating to the players and spectators that an offside has occurred and play is to stop. In case an infraction of the rules incurring a penalty takes place, the official

closes switch 29, thus lighting all the red lights as a signal to stop play, the red color indicating that a penalty is to follow which is then announced over the conventional public address system.

Following stoppage of play the game is restarted by a face-off along a line indicated by the official through manipulation of the green light circuits. If, for example, the offside or rule infraction occurred in center ice, but nearer blue line 14 than line 13, the official closes switch D, lighting the green lights in boxes d so that when the yellow or red lights have been extinguished the green lights define an imaginary line across the rink indicating to the assistant on the ice the position lengthwise of the field at which the face-off is to take place. The pairs of green lights at positions b, c, and e and the opposed pair of lights in the groups a and f define other lines upon which a face-off may be directed to take place by the official through closure of switches B, C, E, A or F respectively.

It will be understood that the number of light positions may be greater or less than that shown and the positions indicated with respect to the playing features of the field, such as the nets and blue lines, by the light combinations may be varied as the rules adopted or the character of the game may require. In general of course the greater the number of green light circuits employed the greater can be the exactness with which the official can direct or indicate the position at which the face-off is to take place.

If desired a greater or less number of color designations may be used. For example, as shown in the modification shown in Fig. 4, the set of lights used to stop the play may also be used to indicate the position of the face-off restarting play. As shown in Fig. 4, the yellow lights used to stop the play and simultaneously indicate that an off-side has occurred, as the reason therefor, are also subsequently used in lieu of the green light circuits, previously described, to start the play both after an offside or the calling of a penalty. In Fig. 4 the stations a, b, c, etc. are provided only with yellow and red lights. As in the arrangement previously described, the red lights are placed across the common return 25 and a line or lead 28, the latter being connected, as before, through switch 20 to the main lead 27. The yellow lights at the several positions a, b, c, d, e, and f are, however, provided with separate circuit leads 39, 40, 41, 42, 43, and 44 controlled by the switches A, B, C, D, E, and F, which previously controlled the green circuits, and which selectively close the circuits of the lights at said several positions. Switch 18 is replaced by a multiple contact switch 45 which simultaneously closes all of the circuits 39 to 44 inclusive to light the yellow lights at all positions when an offside is called. In some games a single set of lights wired and controlled as above described with reference to the yellow lights in Fig. 4 may suffice.

The fact that the stop-play lights are arranged around the entire field assures that one or more will always be within the line of vision of all the players and the spectators as well, and the indication given persists as long as the controlling switch remains closed. Similarly the starting lights may be kept on until all players have taken position, and the official has ascertained, in case substitute players go on the ice, that the substitution is completed. The starting lights are then extinguished as an indication that the as-

sistant may drop the puck for the resumption of play.

While I have shown the control switches as directly controlling the several signal circuits, it will be understood that the diagrams of Figs. 3 and 4 are illustrative only and that conventional relay circuits may be employed where the character of the current or other circumstances require and that the type of switches used and the other wiring details may accord with any standard or desired practice.

I claim:

1. In combination with a playing field, a game officiating device which comprises a plurality of indicators distributed at intervals around said field and visible therefrom, said indicators being positioned in predetermined relation to the playing features of the field which govern play thereon, and switch controlled electrical actuating means for selectively actuating said indicators simultaneously or in predetermined groups.

2. In combination with a playing field a game officiating device which comprises a plurality of electrically operated signal lights distributed at intervals around said field and visible therefrom, said lights being positioned in predetermined relation to the playing features of the said field which govern play thereon, electrical circuits for selectively actuating said lights simultaneously or in predetermined groups, and switches for controlling said circuits.

3. In combination with a playing field a game officiating device which comprises a plurality of electrically operated signal lights distributed at intervals around said field and visible therefrom, said lights including at least two sets of lights differing in color, electric circuits for actuating each of said sets independently, the circuit actuating one of said sets being adapted to actuate predetermined portions of that set selectively to designate predetermined locations on the field, and switches controlling said circuits, said switches being operable from a position commanding a view of the playing field.

4. In combination with a playing field a game officiating device which comprises a set of electrically operated signal lights distributed at intervals around the borders of said field and visible therefrom, said lights being positioned in predetermined relation to the playing features of said field which govern play thereon, electrical circuits for selectively actuating predetermined groups of said lights, at least one other set of signal lights arranged at the borders of said field and visible therefrom, an electrical circuit for actuating the lights of the latter set simultaneously, and switches controlling said several circuits.

5. In combination with a playing field a game officiating device which comprises a set of electrically operated signal lights distributed at intervals around the borders of said field and visible therefrom, said lights being positioned in predetermined relation to the playing features of said field which govern play thereon, electrical circuits for selectively actuating said lights simultaneously or in predetermined groups, a second set of signal lights distributed at intervals around the borders of said field and visible therefrom, an electrical circuit for actuating all the lights of said second set simultaneously, and switches controlling said circuits, said switches being operable from a position commanding a view of the playing field.

6. In combination with a playing field a game officiating device which comprises a set of electrically operated signal lights all of a given color distributed at intervals around the borders of said field and visible therefrom, said lights being positioned in predetermined relation to the playing features of said field which govern play thereon, electrical circuits for selectively actuating said lights simultaneously or in predetermined groups, a second set of signal lights, all of a given color different from that of the first set, distributed at intervals around the borders of said field and visible therefrom, an electrical circuit for actuating all the lights of said second set simultaneously, and switches controlling said circuits, said switches being operable from a position commanding a view of the playing field.

7. In combination with a playing field a game officiating device which comprises a set of electrically operated signal lights of a given color distributed at intervals around the border of the playing field and visible therefrom, means to simultaneously actuate said lights to signal stoppage of play, a set of electrically operated signal lights of a color different from the first set, and means to selectively actuate predetermined portions of the lights of the second group to desig-

nate the position on the field at which play is to restart.

8. In combination with a playing field a game officiating device which comprises a plurality of signals distributed at intervals around the playing field and visible therefrom, means to actuate all said signals simultaneously to signal stoppage of play and means to selectively actuate predetermined groups of said signals to designate the position on the field at which play is to restart.

9. In combination with a playing field a game officiating device which comprises a plurality of signal stations distributed at predetermined positions around the playing field and visible therefrom, at least one electrically operated signal light at each of said stations, electrical circuits for actuating said lights, and switches controlling said circuits including a switch mechanism to establish a closed circuit to each of said stations and switch mechanisms selectively operable prior to the opening of the circuits established by the first named switch mechanism to establish a closed circuit to less than all of said stations independently of said first switch mechanism.
